(Cl. D26—5)

To all whom it may concern:

Be it known that I, Bernhard N. Palm, a citizen of the United States, residing at Newport Beach, in the county of Orange and State of California, have invented a new, original, and ornamental Design for a Motor Casing, of which the following is a specification, reference being had to the accompanying drawing, forming part thereof.

In the drawing

Fig. 1 is a front elevational view of the motor casing, showing my new design;

Fig. 2 is a side elevational view;

Fig. 3 is a rear elevational view; and

Fig. 4 is a top plan view thereof.

I claim:

The ornamental design for a motor casing, as shown.

BERNHARD N. PALM.
